CROSSARM CLEVIS

Frederick George Ridgers, Hamilton, Ontario, Canada, assignor to N. Slater Company, Limited, Hamilton, Ontario, Canada

Application June 10, 1950, Serial No. 167,279

2 Claims. (Cl. 248—220.5)

1

This invention relates to a cross arm insulator mounting.

A mounting according to the invention is intended primarily to be applied to a cross arm at which the conductor is to undergo or subtend a change or deflection in its direction. Usually, the conventional pin (metal or wooden) mounting an insulator is adequate where the conductor is straight; but where the conductor has to undergo a change in its direction, at a particular insulator, the conventional pin may be inadequate to resist the considerable side thrust or horizontal force imposed upon such pin. A special mounting is then necessary.

The objects of the invention, generally, are to improve on known cross arm insulator mountings.

A specific object of the invention is to provide a strong mounting designed to provide maximum strength for a minimum weight of material used, thus reducing the weight and cost of the mounting.

Another specific object is to provide a mounting designed to resist deformation.

Another specific object is to provide a mounting which can be manufactured easily and cheaply.

Another specific object is to design a mounting which will resist displacement upon the cross arm when attached in operative position.

Another specific object is to so design the mounting that the insulator is easily applied and as easily removed.

Still another specific object is to provide a mounting which is held securely to the cross arm by a single bolt and once applied, is held in operative position against lateral displacement or rotary displacement relatively to the cross arm.

In the drawing, wherein like numerals of reference indicate corresponding parts in the various figures.

Figure 1 is a side elevation of a typical insulator in operative position on a mounting made according to this invention;

Figure 2 is an end view of Figure 1, as from right to left;

Figure 3 is a section on line 3—3 in Figure 1; and

Figure 4 shows a modified form of attaching bolt.

Referring now by numerals to the drawing, 10 shows a typical insulator. 11 is a metal strap or bar formed substantially to the shape of a U, presenting two substantially parallel legs, that is, an upper leg 12 and a lower leg 13 extending

from the base 14 of the U. The base 14 is transversely curved inwardly, that is, concavely curved, to add strength and rigidity thereto. The lower leg 13 is adapted to be laid upon the cross arm C, lengthwise thereof.

The radius of curvature of the strap, lengthwise thereof, is chosen to provide ample flash-over clearance (gap) between the conductor T and the strap.

10 The rearward end of the lower leg 13 is formed to present a bent-back portion 17 overlying the leg 13 and extending toward the base 14 of the U-shaped member 11, in spaced parallel relationship to the leg 13 to provide a support for the lower end of the insulator 10.

15 To provide the support or portion 17, and as best shown in Figure 1, the rearward extension which provides the support, is bent upwardly as at 15, and then bent at an angle as at 16 from 20 which the support proper or portion 17 extends. By so forming the extension, more particularly, the portion 16, the distance between the usual tie wire W effectively attaching the conductor T to the insulator 10 is increased, to provide ample 25 flash-over clearance.

The upper leg 12 is so spaced from the support or portion 17 as to provide the space necessary to receive the insulator therebetween.

Straddling the lower leg 13 is an elongated 30 member 18, conveniently formed or pressed from a metal strap or bar. The member 18 is formed to present a recess 19 (see Figure 2) adapted to receive the lower leg 13 proper, and side, slightly inclined portions 20 adapted to engage 35 part of the upper face of the cross arm, the side portions terminating in downwardly-directed or depending flanges 21 adapted to lie closely adjacent to the opposite vertical faces of the cross arm. Thus, when the elongated member 18 and the leg member 13 are held against one another by a bolt 25 (to be referred to later), both members are held against substantial lateral relative displacement, and the U-shaped member 11 is also held against lateral displacement relatively 40 to the cross arm as well as against rotary displacement on the axis of the bolt 25.

One end of the elongated member 18 terminates in an upwardly-curved portion 24 adapted to engage part of the curved lower portion of the 45 base 14 of the member 11 effectively to add strength and rigidity to the member 11, more particularly, to the curved lower end of the base 14. This arrangement makes for a simplified, and therefore cheaper, but sturdy device.

50 The legs 12 and 13, the elongated member 18

and the insulator support 17 are provided with aligned holes to receive a conventional cotter bolt 27 by which the insulator is attached in operative position to the mounting. The bolt is locked in position by a cotter pin 29 passed through the bolt 27 at a point below the support 17.

The lower leg 13 of the U-shaped member 11 and the elongated member 18 are held in co-engaging, straddled relationship, and held to the cross arm, by the bolt 25 aforesaid—a carriage bolt. The hole through the elongated member 18 for the square shoulder of the bolt 27 is so positioned relatively to the upwardly curved end 24 of the member 18, that the curved end is in contact with the lower curved portion of the base 14 of the member 11. The shank of the bolt is threaded throughout, to receive a nut 33, so that the nut serves to hold the leg 13 and the elongated member 18 in tight engagement or contact. The nut 33 may be generally tapered and made to a diameter slightly less than the conventional tapered hole provided in cross arms for the reception of wooden pins. The mounting may thus be assembled and applied as a unit to the cross arm, the unit being held in operative position as by a washer 36 and nut 37.

The nut 33 is generally tapered to be received tightly into the upper portion of the vertical hole through the cross arm. To facilitate the tightening of the nut in position, diametrically disposed wrench flats 38 are provided on the nut.

Cross arms are sometimes provided with vertical holes adapted to receive steel insulator supporting pins, in lieu of wooden pins. To adapt the mounting to the use of such a cross, the carriage bolt 25 and nut 33 may be replaced by a stud 40 such as shown in Figure 4. The stud includes an integral collar 41 and has its opposite ends threaded to receive an upper nut 42 and the nut 37 and washer 36 (shown in Figures 1 and 2). The nut 42 and collar 41 operate to hold the elongated member 18 and the leg 13 together, as well as operatively attached the mounting to the cross arm, that is, they have the function served by the carriage bolt 25 and nut 38 aforesaid.

The carriage bolt 25 (or the stud 40, as the case may be) is positioned as far away from the end of the leg 13 as possible. When the direction of the conductor T changes at the insulator, a very great pressure or force is imposed horizontally upon the insulator in a direction away from the base 14 of the U-shaped mounting 11 (the mounting is always attached to the cross arm so that the force is against, and not away from, the insulator). The mounting tends to rotate with respect to the cross arm, longitudinally thereof, on the outer end (the right-hand end as seen in Figure 1) of the leg 13. The turning moment, being pressure times the vertical distance between the conductor and the upper face of the cross arm, is resisted by the turning moment defined by the distance between the outer end of the leg 13 and the axis of the bolt 25. Thus, the greater such distance is, the less is the tension imposed upon the bolt. As under such conditions of deflection of the conductor at the insulator, a horizontal force is also imposed upon the leg 12, tending to deform the U-shaped member 11, the curved rear-

ward extension 24 of the elongated member 18 to some extent resists the deformation of the U-shaped member or mounting.

It is to be understood that the term "bolt" in the claims is not to be a limitation of the scope of such claims but is to include any mechanical equivalent.

What I claim is:

1. In a cross arm insulator mounting, a substantially U-shaped member one leg of which is in part flat to lie upon the cross arm, longitudinally thereof, said leg including a rearward portion overlying said one leg in spaced relationship thereto, an elongated member adapted to straddle said one leg and prevent relative lateral displacement thereof, said portion being spaced from the other leg of said U-shaped member to receive the insulator therebetween and forming a support therefor, said elongated member terminating at one end in an upwardly curved extension adapted to engage a lower curved portion of the base of said U-shaped member, and a bolt for securing said elongated member and said one leg in straddled, coengaging relationship and to the cross arm, said portion and at least said other leg having aligned holes for the reception of the bolt by which the insulator is operatively attached to the mounting, said first named bolt being positioned nearer to said curved extension than the axis of said aligned holes.

2. In a cross arm insulator mounting, a metal strap longitudinally bent into substantially the form of a U to present a pair of generally parallel legs extending from the base of the U of which one leg is in part flat and is adapted to be laid lengthwise upon the cross arm, said one leg terminating in a rearward portion extending toward the base of the U in spaced parallel relationship with said one leg to form a support for the insulator when in operative position between said portion and the other leg of said strap, the base of the U being concavely formed, a second metal strap of generally channelled form adapted to straddle said one leg and in part encompass the cross arm, said second strap terminating at one end in an upwardly curved extension adapted to engage a lower curved portion of said base, and a bolt securing said one leg and said second member in straddled relationship and adapted to pass through the cross arm whereby to attach the mounting thereto, said legs, said portion and said second metal member having aligned holes for the reception of the bolt attaching the insulator to the mounting, said first-named bolt being positioned nearer to said base than the axis of said aligned holes.
